UNITED STATES PATENT OFFICE.

EUGENE SILVER, OF OMAHA, NEBRASKA.

GASOLENE-ENGINE PRIMER.

1,030,931.

Specification of Letters Patent. Patented July 2, 1912.

Application filed January 27, 1912. Serial No. 673,841.

To all whom it may concern:

Be it known that I, EUGENE SILVER, a citizen of the United States, residing at Omaha, in the county of Douglas and State 5 of Nebraska, have invented certain new and useful Improvements in Gasolene-Engine Primers, of which the following is a specification.

This invention relates to improvements in 10 gasoline engine primers, and has for its object, broadly, to provide an attachment so constructed that it may be conveniently mounted upon or applied to any gas engine for the distribution to each of the cylinders 15 such a limited or measured supply of gasoline or kerosene as may be required for emergency purposes, the same to consist of few and simple parts and to be effective in operation.

20 The invention has reference to a combination check valve and spraying device for each cylinder in communication with a distributing pipe, by means of which equal quantities of the gasoline may be injected 25 and atomized within the cylinders, a pump being employed for elevating the oil and supplying the distributing pipe.

The invention also includes a manifold 30 provided with means for a supply of the liquid fuel from the distributing pipe, under control of an operator, this being found useful in connection with the priming of the cylinders; also it includes means for conducting a limited, measured supply of kerosene or similar fuel to the cylinders, and 35 manifold, for burning and cleaning the walls of these chambers when they become foul.

With these objects in view the invention 40 presents a novel and useful construction, combination and arrangement of parts as described herein and claimed, and as illustrated in the drawing, it being understood that changes in form, size, proportion and 45 minor details may be made within the scope of the claims without departing from the spirit of the invention or sacrificing any of its advantages.

In the drawing, Figure 1 shows a side elevation of an automobile, parts being broken 50 and in section. Fig. 2 is a detail relating to Fig. 1, showing, in plan, the relative position of certain parts. Fig. 3 is a sectional view of a conducting tube as on line *a a* of 55 Fig. 5. Fig. 4 is a transverse section of a conducting tube on line *b b*, of Fig. 6. Fig.

5 is a view in longitudinal section, of a housing for one of the combination check valve and spray nozzles employed for each of the cylinders. Fig. 6 is a view, in longitudinal section of the housing for the check valve of the conducting pipe communicating with the distributing pipe and the manifold. Fig. 7 is a view in longitudinal section of the distributing pipe, and pipes communicating with the cylinders and manifold.

60 Referring now to the drawing for a more particular description, numerals 1 indicate the cylinders, and 2 indicates the manifold of a gasoline engine 3 mounted upon an automobile 4, the gasoline tank, carbureter and pipe line therebetween being respectively indicated at 4', 5 and 6.

70 In the operation of gasoline engines used in connection with automobiles, it will be understood that the manifold is supplied with carbureted air from the carbureter for charging the cylinders, this being by suction during the rotation of the engine shaft. However, when the engine is not operating, 75 the hydrocarbon of the mixture of hydrocarbon and air, when the temperature is low, may be condensed and may return to the carbureter by action of gravity, with the result that the engine must thereafter be manually "cranked" in order that its shaft may again commence to rotate. I have ascertained that, by supplying the manifold with a limited quantity of gasoline, the engine 80 may be started without "cranking", provided a small amount of the oil is also supplied, in atomized form, to the cylinders, and therefore I provide above the cylinders the horizontal distributing pipe 7 for a liquid fuel, the supply of gasoline being the 85 conducting pipe 8, having a connection at 9 with the pipe 6. By use of a pump 10, gasoline may be elevated from pipe 6 and compressed within the distributing pipe; and the oil may be atomized within the cylinders 90 by causing it, while under pressure, to pass through the comparatively small aperture or channel 11 of nozzle 12 of each housing 13, the housings being mounted upon the walls and the nozzles projecting within the 95 cylinders.

100 Mounted at uniform longitudinal intervals upon pipe 7 are tubular members 14 having limited bores, comparatively; they extend between and are in communication with the distributing pipe and chambers 15 of housing-members 13. In each of these hous-

ing-members is formed a second chamber 16. Between chambers 15 and 16 is formed the passageway 17. A comparatively strong spring 18 is seated in each chamber 16 said spring being provided with a ball valve 19 to prevent any movement of air or gas or flow of oil outwardly of the cylinder, and to resist with considerable force, the passage of oil within a cylinder.

10 At 20 is indicated a conducting pipe providing a conduit for oil from the distributing pipe 7 to the manifold. A casting or valve housing 21 is provided and is threaded in the wall of the manifold. It is provided with chambers 22 and 23. Between and communicating with these chambers is a comparatively large aperture 24; and opening within the manifold and communicating with chamber 23 is an aperture 25 having a comparatively large bore. A spiral spring 26 is mounted within chamber 23 and the spring is provided with a ball valve 27. Spring 26, is constructed of light material and while it effectively prevents the passage of oil or air outwardly of the manifold, it offers only a slight resistance to the passage of oil from pipe 7 to the manifold.

Pipe 8 is provided with check valve 28 which prevents a return of the oil after it enters the pump from pipe 6, and the distributing pipe is provided with stop cock 29. When starting the engine, all that is necessary, after the pump handle has been 35 lifted, is to move the handle of the pump downwardly, cock 29 being open. By action of the pump, since check valve 28 at this time will be closed, oil will enter and will be compressed in pipe 7, and this pipe operates as an equalizing chamber, and therefore oil in uniform quantities will be injected within each cylinder, and since it will pass out of the nozzles with considerable force, it will be atomized, ready to be ignited 45 by operation of a spark-plug (not shown), and by these means the cylinders are primed for the purpose described. At the time the oil is atomized in the cylinders by the downward movement of the pump handle, a supply of oil will flow through passageway 25 within the manifold. It will not be atomized however, since spring 26 is of such construction that it offers only a slight resistance to the oil, a nozzle not being employed.

55 The parts are so adjusted and are of such proportion that a sufficient quantity of oil will pass within the manifold to maintain the cylinders for ten or twelve revolutions of the engine shaft, at which time, by operation of suction, the manifold will be supplied with fuel from the carburetor. Thereafter, while the engine is operating, all of the oil which remains in the distributing pipe 7 will pass within the cylinders and 65 manifold from suction, stop cock 29 being

closed. Since springs 18 are stronger and provide a greater resistance, the greater part of the oil by operation of suction will pass within the manifold. The operation just described may be repeated, as often as required, and the use of the crank for starting the rotation of the engine shaft may be avoided.

It is necessary occasionally to clean the interior walls of the cylinders and manifold, since they become foul, and this is best accomplished by use of kerosene.

At 30 is indicated a supply receptacle for kerosene oil, said receptacle having a conducting pipe 31 provided with a 3-way valve 32. By manually rotating the cylinder of the 3-way valve 32, a flow from pipe 8 will be prevented and a supply of kerosene may be drawn within the barrel of pump 10, and the cylinders and manifold may be charged with the kerosene, by use of the pump, in the manner already described. The barrel of the pump is preferably constructed of glass, so that its contents and operation may be visible. While I have shown the pump and reservoir for the kerosene as mounted upon the dash of the automobile, they of course, may be located upon some other part, if desired.

Among some of the advantages of the herein described priming attachment, it may be stated that the parts are few and convenient in manufacture, and it may be mounted operatively, by any mechanic of ordinary skill, without changing any of the original parts of an engine, and by its use the objectionable and often dangerous practice of "cranking the engine" may be avoided. Kerosene has for a long time been used as a preferred substance to be burned within the cylinders and manifold as a cleaning agent, but these parts have not been convenient of access. As already explained, the kerosene, while entirely separated from the gasoline, may be readily conducted to these parts, and no additional carrier for kerosene is needed, than the devices described.

Having fully explained my invention, what I claim and desire to secure by Letters Patent is,

1. In combination with the cylinders and manifold of a gasoline engine, a distributing pipe for liquid fuel disposed horizontally above the cylinders and manifold, said pipe having a plurality of tubular members, each being in communication with a cylinder, and provided with a conduit communicating with the manifold; a valve provided for the conduit and for each of said tubular members; and means to compress the liquid fuel within the distributing pipe for actuating said valves.

2. A priming device for gasoline engines, comprising, in combination with the cyl-

inders and manifold, a distributing pipe for liquid fuel provided at longitudinal intervals with tubular members and having a conduit communicating with the manifold; 5 spraying-members projecting within the cylinders and connected with the tubular members; a check valve provided for the conduit; a check valve provided for each of said tubular members; and means to 10 compress the liquid fuel within the distributing pipe to open said valves.

3. A priming attachment for gasoline engines, comprising, in combination with the manifold and cylinders, an elongated equalizing chamber adapted to contain a liquid fuel under pressure, and provided at uniform longitudinal intervals with tubular members; spray-members in communication with the tubular members and provided with 20 check valves, said spray-members being mounted upon and having nozzles projecting within the cylinders; and a conducting pipe provided with a check valve and communicating with the manifold and said 25 equalizing chamber.

4. A priming attachment for gasoline engines, comprising, in combination with the manifold and cylinders; a distributing pipe adapted to contain gasoline under pressure; 30 tubular members in communication with the distributing pipe, each of said tubular members being provided with a check valve and having a nozzle with a limited bore, each of said tubular members being mounted 35 upon and having its nozzle projecting within a cylinder; a conducting pipe provided with a check valve, said conducting pipe being in communication with the distributing pipe and said manifold and having intake and 40 discharge ports of greater bore than the bores of the nozzles of the tubular members.

5. A priming attachment for gasoline engines, comprising, in combination with the cylinders and manifold; a distributing pipe; 45 a pump for compressing within the distributing pipe a liquid fuel; a cylindrical housing mounted upon each cylinder and

upon said manifold; a resiliently mounted check valve mounted in each cylindrical housing; and a plurality of conducting pipes 50 in communication with the distributing pipe, each of said pipes being in communication with one of said cylindrical housings.

6. A priming attachment for engines of the internal combustion type, comprising, in combination with the cylinders and manifold of the engine, a pump; a distributing pipe connected with the pump, a supply pipe connected with said pump; means to terminate the connection of the distributing pipe 60 with the pump; means to terminate the connection of the supply pipe with said pump; a spray-member provided for and projecting within each cylinder; tubular members provided with check valves communicating 65 with the spray-members and the distributing pipe; and a conducting pipe provided with a check valve for communicating with the distributing pipe and said manifold.

7. A priming attachment for gasoline engines, comprising, in combination with the cylinders and manifold thereof; a pump; a distributing pipe in communication with said pump and provided with a check valve; a gasoline tank; a supply pipe provided 70 with a check valve and in communication with the gasoline tank and said pump; a kerosene receptacle; a supply pipe provided with a check valve and in communication with the kerosene receptacle and said pump; a plurality of tubular members, each being provided with a check valve and in communication with the distributing pipe and one of said cylinders; and a conducting pipe provided with a check valve and communicating 75 with the distributing pipe and said manifold.

In testimony whereof I have affixed my signature in presence of two witnesses.

EUGENE SILVER.
